UNITED STATES PATENT OFFICE.

LAWRENCE W. LUELLEN, OF MOUNTAIN LAKES, NEW JERSEY, ASSIGNOR TO INDIVIDUAL DRINKING CUP COMPANY, OF NEW YORK, N. Y., A CORPORATION OF MAINE.

CATAMENIAL BANDAGE.

1,192,439.

Specification of Letters Patent. Patented July 25, 1916.

Application filed September 11, 1913. Serial No. 789,398.

To all whom it may concern:

Be it known that I, LAWRENCE W. LUELLEN, a citizen of the United States, residing at Mountain Lakes, county of Morris, 5 and State of New Jersey, have invented certain new and useful Improvements in Catamenial Bandages, of which the following, taken in connection with the accompanying drawings, is a full, clear, and concise description thereof.

My present invention comprehends as a new article of manufacture, a catamenial bandage of a form which will conform to and afford complete protection to the body 15 of the user and one which possesses great retentive capacity for the menstrual discharge.

In the accompanying drawings, I have illustrated an embodiment of my invention 20 in which,

Figure 1 is a perspective view of a catamenial bandage made in accordance therewith. Fig. 2 is a longitudinal sectional view, and Fig. 3 is a cross-sectional view 25 thereof taken on line *a*—*a* of Fig. 2.

In carrying my invention into practice, I use a covering or envelop of soft absorbent fabric *a* preferably cotton woven in tube form with a filling of cotton *b* or other suitable absorbent material distributed throughout an intermediate portion of the tube covering. I then stitch the ends of the filling and the covering together as at 1 forming a complete closure for the filling and insuring its retention in an evenly distributed condition. When formed in this manner, the fabric covering is provided with free ends 2 of superimposed layers of sufficient length to be attached to the apparel of the user by any suitable means. I then take the bandage and impart to it its final form and preferably do this by machinery when wrapping the same into individual packages suitable for distribution through vending 45 machines.

I will proceed to describe the method employed for wrapping and packing the bandage into its final commercial form which imparts to it the desired shape, which it assumes upon being abstracted or removed from its package.

The edges 3 and 4 of one of the free ends 2 are reversed or folded over upon the central portion. In this position, the end is 55 rolled on a mandrel when the thickened por-

tion caused by the filling is reached, suitable guide plates or mechanism is brought into engagement with the edges 5 and 6 as the bandage passes through the wrapping machine. The material along these edges is 60 caused to be rolled toward the center of the bandage and to be slightly compressed. This causes the longitudinal edges 7 and 8 running lengthwise of the bandage to become thickened, so that the central portion 65 9 will be somewhat depressed and lowered so as to form a trough-like structure as illustrated. This operation also narrows or reduces the width of the bandage when it is delivered in its rolled form ready for wrapping. 70

The bandage is caused to retain its shape owing to the fact that it is formed and tightly wound into package form and retained under compression, so that when removed from the package, it assumes the trough-like formation shown more clearly in Fig. 2.

Having thus described my invention what I claim as new herein and desire to secure by Letters Patent is:

1. As a new article of manufacture, a substantially rectangular catamenial bandage comprising a woven tube of absorbent fabric with a filling of absorbent material of 85 trough-like formation distributed throughout an intermediate portion thereof, said material being stitched at its ends to the fabric.

2. As a new article of manufacture, a 90 substantially rectangular catamenial bandage comprising superimposed layers of absorbent fabric with a filling of absorbent material distributed throughout an intermediate portion thereof, said material being in the 95 form of a trough with its edges in lengthwise direction relatively thicker than its central portion.

3. As a new article of manufacture, a 100 catamenial bandage comprising superimposed layers of absorbent fabric with a filling body of absorbent material pocketed therein and stitched at its ends thereto, the edges of said absorbent material in lengthwise direction being thicker than the intermediate center portion.

4. As a new article of manufacture, a 105 catamenial bandage comprising superimposed layers of absorbent fabric with a filling body of absorbent material pocketed 110

therein and stitched at its ends thereto, said body of absorbent material being tapered toward its ends with its edges in lengthwise direction thicker than the intermediate center portion so as to form a trough extending substantially lengthwise between thickened portions thereof.

In witness whereof I have hereunto set my hand in the presence of two subscribing witnesses.

LAWRENCE W. LUELLEN.
